US00D853576S

(12) **United States Design Patent** (10) **Patent No.:** **US D853,576 S**
Ma (45) **Date of Patent:** **** Jul. 9, 2019**

(54) **MASSAGER**

(71) Applicant: **SHENZHEN BREO TECHNOLOGY CO., LTD.**, Shenzhen, Guangdong OT (CN)

(72) Inventor: **Xuejun Ma**, Guangdong (CN)

(73) Assignee: **SHENZHEN BREO TECHNOLOGY CO., LTD.**, Shenzhen (CN)

(**) Term: **15 Years**

(21) Appl. No.: **29/639,388**

(22) Filed: **Mar. 6, 2018**

(30) **Foreign Application Priority Data**

Sep. 7, 2017 (CN) 2017 3 0423056

(51) **LOC (11) Cl.** **28-03**

(52) **U.S. Cl.**

USPC **D24/215**

(58) **Field of Classification Search**

USPC ..... 601/15, 18, 19, 46, 47, 48, 52, 99, 112, 601/113, 118, 125, 129, 134, 135, 137, 601/DIG. 12, DIG. 14, DIG. 15, DIG. 16, 601/DIG. 17; D24/133, 200, 211, 212, D24/213, 214, 215; 600/38, 39, 40, 41; D30/160; D4/100, 109, 127

CPC A61H 23/004; A61H 2201/0153; A61H 2201/1645; A61H 7/007

See application file for complete search history.
